UNITED STATES PATENT OFFICE.

CLIFTON CHISHOLM, OF SAN FRANCISCO, CALIFORNIA, ASSIGNOR TO PLANOSTYLE COMPANY, A CORPORATION OF CALIFORNIA.

OFFSET PRINTING AND ADDRESSING PRESS.

1,197,182.

Specification of Letters Patent.

Patented Sept. 5, 1916.

Application filed June 29, 1914. Serial No. 848,501.

To all whom it may concern:

Be it known that I, CLIFTON CHISHOLM, a citizen of the United States, residing in the city and county of San Francisco and State of California, have invented a new and useful Improvement in Offset Printing and Addressing Presses, of which the following is a specification.

My invention relates to offset printing presses for printing addressed circulars and the like, wherein a printing cylinder and a series of address plates, each bearing an impression of an address and a salutation, operate in conjunction with a rotating offset cylinder, a rotating printing cylinder, paper feeding mechanism, and a scrubbing roll; and the objects of my invention are first, to provide improved means for printing circular letters each having the same letter head, body and signature, but with a different address and an appropriate salutation on each circular letter; second, to provide improved means for imparting an impression of a circular letter having the same letter head, body and signature to the offset cylinder at each rotation thereof; third, to provide improved means for imparting an impression of a different address and appropriate salutation to the offset cylinder in proper relation to the impression of the letter thereon at each rotation thereof; fourth, to provide improved means for feeding a sheet of paper between a platen and the offset cylinder and to transfer the impression from the offset cylinder to the sheet of paper at each rotation thereof; fifth, to provide improved means for removing the remaining impression of the address and salutation from the offset cylinder after a sheet of paper has received an impression therefrom; sixth, to provide improved means for imparting an impression of several different addresses, without the salutations, from the same address plates that are used for addressing the letters, to the offset cylinder at each rotation thereof; seventh, to provide improved means for feeding several envelops, one for each address, between a platen and the offset cylinder at each rotation thereof and to transfer the impressions from the offset cylinder to the envelops; eighth, to provide improved means whereby the scrubbing roll may engage and remove the remaining impression of several addresses from the offset cylinder

at each rotation thereof; ninth, to provide means whereby the position of the impression of the body of the letter on the offset cylinder may be adjusted relatively to the position of the impression of the address on the said cylinder; tenth, to provide improved means for dispensing a fluid to, and moistening the surface of, the printing and address plates which will permit only the impression thereon to receive ink; eleventh, to provide means operating in conjunction with the offset cylinder that will remove one address plate at a time from a container and carry the said plate over suitable moistening and inking devices and transfer an impression of the matter thereon onto the offset cylinder at each rotation thereof; twelfth, to provide means that will transfer an impression of the address portion only of several address plates onto the offset cylinder at each rotation thereof; thirteenth, to provide means for receiving the address plates from the delivery end of the carrier and inserting the said plates into a second container in the same order in which the said plates were arranged in the first container; fourteenth, to provide means for feeding one sheet of paper at a time to the offset cylinder at each rotation thereof; fifteenth, to provide an attachment to the paper feeding mechanism that will feed several envelops to the offset cylinder at each rotation thereof; sixteenth, to provide means for changing the speed of the feed rollers relatively to the offset cylinders; seventeenth, means for inking the letter head, body and signature, each a different color; eighteenth, means for changing the colors applied to the letter head, body and signature of the letter; and nineteenth, means for preventing the engagement of inking rollers with the printing cylinder. I accomplish these several features by means of the device disclosed in the drawings forming a part of the present specification, wherein like numerals of reference are used to designate similar parts throughout the said specification and drawings, and in which—

Figure 1 is a side elevation of the device with the upper portion of the second container partially broken away, disclosing the relative positions of the offset and the printing cylinders, scrub roller, the address plate carrier, the inking mechanism for the print

ing cylinder and the address plate carrier, and the rock shaft and levers secured thereto for operating the paper feeding mechanism. Fig. 2 is a plan view of the entire 5 machine disclosing the manner in which the address plate carrier is secured above the offset and printing cylinders and arranged relatively to the said cylinders. Fig. 3 is a front elevation of the device. Fig. 4 is a 10 rear elevation of the machine disclosing the address plate container secured to the back portion thereof. Fig. 5 is a longitudinal, sectional view taken on line X—X of Fig. 2 of the drawings and in the direction indicated by the arrow. Fig. 6 is a sectional view taken on line Y—Y of Figs. 1 and 2 of the drawings, in the direction indicated by the arrows, disclosing a sectional view of the frame, a shaft rotatably and slidably 15 mounted in the frame, a sleeve slidably and rotatably mounted upon the said shaft and the offset cylinder rotatably mounted upon the sleeve, also the transmission mechanism and clutch operating in conjunction therewith, the cams for operating the rock shaft of the paper feeding mechanism, the plates above and below the offset cylinder and the latch for retaining the shaft in one of two 20 positions. Fig. 7 is a broken detailed sectional view of the shaft and sleeve upon which the offset cylinder is rotatably mounted, said offset cylinder being removed therefrom, disclosing the manner in which the clutch on the said shaft engages the clutch 25 member of the transmission. Fig. 7^A is a detailed broken view of the spring latch for retaining the shaft of the offset cylinder in either one of two positions. Fig. 8 is a vertical sectional view taken on lines Z—Z of 30 Figs. 1 and 2 of the drawings, in the direction indicated by the arrows, disclosing a shaft rotatably mounted within the frame, the printing cylinder on the shaft, the cam on one end of the said printing cylinder 35 for imparting a reciprocating movement to certain inking rollers and the cams on the opposite end, which regulate the different colors to be applied to the printing plates on the printing cylinder. Fig. 9 is a broken 40 detailed view of one end of the offset cylinder disclosing the means for tightening the rubber blanket on the offset cylinder and the scrub roller geared to the platen below the offset cylinder, and the cams for preventing 45 the engagement of the scrub roller with the periphery of the offset cylinder, excepting at one portion thereof, representing the relative location of one open portion of the cams for removing the impression of the 50 address as in printing letters, where only one address impression is to be imparted to the offset cylinder at each rotation thereof. Fig. 10 is a view similar to Fig. 9, but disclosing the cams in different positions, so 55 as to provide three recesses into which the 60 retaining roller of the scrub roller may drop so as to allow the said scrub roller to engage the periphery of the offset cylinder at three different positions, as when imparting three different impressions of three different addresses to the said offset cylinder at each rotation thereof when addressing envelopes. Fig. 11 is an end elevation of the printing cylinder and the different colored inking mechanism therefor, disclosing a series of 65 cams movably mounted on the end of the cylinder and adapted to permit the engagement of only one inking mechanism at a time with certain portions of the periphery of the said printing cylinder. Fig. 12 is a 70 view similar to Fig. 11 of the drawings, but disclosing the cams arranged in a different position so as to change the colors to be imparted to certain portions of the matter on the printing plates on the printing cylinder. 75 Fig. 13 is a view similar to Figs. 11 and 12 with the inking mechanism removed and disclosing the means for shifting, or withholding entirely, the inking mechanism from the periphery of the printing cylinder. 80 Fig. 14 is a bottom plan view of the cams, as disclosed in Fig. 13 of the drawings. Fig. 15 is a view similar to Fig. 13 of the drawings, but disclosing the cams thereon in a different position in order to change the 85 coloring of certain portions of the body of the letter on the printing cylinder. Fig. 16 is a broken sectional view of the receiving end of the carrier, the container containing address plates, the stationary and 90 movable racks, the address plate supporting platform slidably mounted upon the stationary rack, the pawls secured to the said platform and adapted to engage the racks for the purpose of supporting the said platform, a portion of the rock shaft secured to the front of the machine, and the rod connected to the rock shaft and adapted to raise the sliding platform a distance equal to the thickness of one plate at each oscillation of 95 the said rock shaft. Fig. 17 is a broken 100 sectional plan view of the stationary and movable racks disclosing a portion of the plate supporting platform thereon and the manner in which the triple pawls, pivotally secured to the said platform, engage the stationary and movable racks. Fig. 18 is a detailed elevation of a portion of the platform with one plate thereon and the manner in which the projections on the carrier tapes engage the said address plate. Fig. 19 is a broken longitudinal, sectional view of a container with the sliding platform shown therein supporting a plate, the spring latches at the bottom of the said container 110 for preventing the plates from dropping therefrom and the manner in which the spring latches near the upper end of the container prevent the address plates from 115 being moved to the extreme top of the con- 120 125 130 135 140 145 150

tainer. Fig. 20 is a broken detailed view of the top of the container disclosing the manner in which the inclined projections on the sides of the carrier frame engage the upper spring latches on the container and remove the same from above the uppermost address plate on the movable platform within the container, also the manner in which the carrier tapes engage either end of an address plate. Fig. 21 is a broken sectional view of the moistening device disclosing the absorbent outer covering, the perforated cylinder, the rubber covered spring within the cylinder for regulating the flow of the fluid from within the said cylinder and the threaded sleeve and disk for regulating the tension or compression of the rubber coated spring. Fig. 22 is a transverse sectional view of the cylinder disclosed in Fig. 21 of the drawings. Fig. 23 is a vertical sectional view through the carrier frame and platen therein and the inking roller, which inks the impression of the address and salutation on the address plate, also the clutch for releasing the inking mechanism from the driving mechanism and for shifting the inking roller which contacts with the address plate. Fig. 24 is a detailed sectional view taken on line E—E of Fig. 23 of the drawings, of the inking roller and platens therefor disclosing the position of the segmental inking roller for inking the impression of the address and salutation both on the surface of the address plate. Fig. 25 is a view similar to Fig. 24 of the drawings, but disclosing the segmental inking roller in a position where it will ink the address portion only of the address impression and not the salutation thereon. Fig. 26 is an end elevation of the gear and the clutch in the position for inking the entire impression of the address and salutation on the address plate. Fig. 27 is a view similar to Fig. 26 but disclosing the position of the clutch when the address portion only and not the salutation is to be inked. Fig. 28 is a broken side elevation of the delivery end of the carrier disclosing the rock shaft and the connections to the rock shaft by means of which the plate is received from the carrier and inserted into the second container to which the address plates are to be inserted after having been impressed onto the offset cylinder. Fig. 29 is a detailed view on line B—B of Fig. 28 of the drawings, in the direction indicated by the arrow. Fig. 30 is a vertical sectional view of the delivery end of the carrier disclosing a portion of the periphery of the offset cylinder and the platen in contact therewith and an address plate between the said platen and the offset roller, the elevator for inserting the plates into the receiving container and the latch whereby the container is locked in front of the receiving end of the carrier. Fig. 31 is a sectional view taken on line C—C in Fig. 28 of the drawings, in the direction indicated by the arrow, disclosing the levers and the runways by means of which address plates are conveyed from the delivery end of the carrier to the receiving container. Fig. 32 is a broken perspective view disclosing the manner in which one end of one of the delivery levers rides on the runways and engages the offset end of the address plate. Fig. 33 is a sectional view taken on line D—D of Fig. 16 of the drawings in the direction indicated by the arrow. Fig. 34 is a vertical sectional view of the envelop container and the envelop feeding attachment secured to the reciprocating table of the sheet paper feeding mechanism, also disclosing the manner in which a portion of the sheet feeding mechanism is folded onto the table when not in use, the rock shaft and the levers secured thereto for operating the reciprocating table for the sheet paper mechanism and the feed rollers geared to the transmissions. Fig. 35 is a broken plan view of the envelop feeding plate. Fig. 36 is a diagrammatic view of a sheet of paper disclosing the approximate positions of the letter-head, date, body and signature of a letter and the relative position of the impression of the address and salutation to the body of the letter, that portion inclosed by the dotted rectangle representing an impression of the address and salutation and indicating also the area which would be inked by the address plate inking mechanism when the salutation is included. Fig. 37 is a diagrammatic view of an envelop addressed by the same address plate, the larger dotted rectangle indicating the area inked by inking mechanism for the address plate, which does not include the salutation, the segmental inking roll for inking impressions on the address plate having been shifted so as to include the address portion only and not the salutation.

The present state of the art discloses various devices for addressing envelopes and circulars, but in most types of this class of machines for printing addresses it is the present practice to first, print on a sheet of paper the body, signature and letter-head of the letter. In order to fill in the address it is the present practice to run the same letters through an addressing machine in order to supply a different address to each circular letter.

I propose to provide a printing press whereby the letter may be typed on a typewriter directly onto a flexible offset printing plate. The said plate to be signed in the usual manner and applied to the printing cylinder of an offset printing press.

A drawer or container, containing a series of address plates, each containing an impression of a different address and appropriate salutation therefor, is provided with a

110
115
120
125
130

removable end and means for retaining the plates in the said container when the end has been removed. This drawer or container is inserted bodily into the machine 5 and a second empty container placed at the delivery end of a carrier, one address plate at a time is removed from the first drawer or container and conveyed over suitable inking and moistening devices, and transfers a 10 design or an impression of the said address and salutation on the offset cylinder in its proper position relative to the body of the letter which has been transferred or impressed on the offset cylinder from the printing cylinder. In other words, the offset cylinder receives an impression of the letter-head, body and signature of the letter from the printing cylinder and an impression of a different address and appropriate 15 salutation at each rotation of the said offset cylinder, each rotation of the offset cylinder also causing a sheet of paper to be fed between the said cylinder and a platen rotatably mounted thereunder and suitable cams 20 on the end of the offset cylinder permit the engagement of a scrub roller with that portion of the periphery of the said offset cylinder, containing the address and salutation portion only, which will remove whatever 25 impression or ink remains of the said address and salutation after the same has been impressed onto the letter, so that as clean a surface as possible may be presented to the succeeding address plate, in order to receive 30 an impression of a new address and appropriate salutation therefor; also each rotation of the offset cylinder operates means which will convey an address plate, from which the design has been impressed onto the said 35 offset cylinder, and insert the same into a second container or drawer with the end removed therefrom, in the same order in which the address plates were arranged in the first container. I have also provided 40 means whereby the printing cylinder may be disengaged from the offset cylinder and, without increasing the speed of the carrier, select three address plates and impress the 45 impressions of the same onto the periphery of the offset cylinder at each rotation thereof, also means whereby the speed of the feed rollers in relation to the speed of the offset cylinder will be increased and the paper feeding mechanism will be converted into 50 an envelop feeding plate so that in place of printing one letter and address and salutation therefor, at each rotation of the said offset cylinder, three addresses only, the salutation portion having been omitted, will be 55 impressed onto the offset cylinder, thus addressing three envelops therefrom at each rotation of the said offset cylinder.

Briefly, the machine may be used for printing a series of circular letters, each 60 having a different address and appropriate

salutation therefor, and the same plates may be used to address a series of envelops.

The invention consists mainly of what I term the side frames 1, and sub-frames 2 for the support of the paper feeding mechanism, 70 hereinafter more fully described. A printing cylinder 3 is rotatably mounted upon a shaft 4, provided with a handle 5, said shaft 4 being in turn rotatably mounted within eccentric sleeves 6 that are in turn rotatably mounted within suitable pockets in each side frame 1, so that the said shaft 4 may be adjusted independently at each end thereof by means of partially rotating the said eccentric sleeves 6, the purpose of which is 80 to adjust the position of the printing cylinder to the offset cylinder. Elastic printing plates 7 are secured in any suitable manner to the periphery of the printing cylinder 3. The said printing cylinder 3 has a cam 8 integral with one end thereof upon which ride the rollers 9 of separate sleeves operatively connected to distributing rollers of the inking mechanisms for inking the address plates and the printing cylinder. 85 Four sectors 11, in four different planes, are rotatably and adjustably mounted upon the shaft 4 at the opposite end of the printing cylinder 3 and are arranged to engage the rollers, which, for purposes of better illustration I shall hereinafter refer to as the riders 12, of the printing cylinder inking mechanisms 14 and 16. 90

Two printing cylinder inking mechanisms 14 and 16 are provided so that two colors 100 may be employed in inking different portions of the design or the impressions of the letter-head, body and signature of the circular letters impressed upon the said printing plates 7. The sectors 11 are arranged to be placed in different positions circumferentially so as to engage the riders 12 of the inking mechanisms 14 and 16 alternately and to prevent the contact of the inking roller in one inking mechanism, containing one color, with the surface of the printing plates 7 while the inking roller of the other inking mechanism, containing another color, is in contact with the said plate 7. By moving the sectors 11 to different 105 relative positions it will be readily observed that different colors will be supplied to the different portions of the plates 7, that is, supposing the colors employed to be blue and black, one set of sectors 11 will prevent the engagement of the blue inking mechanism with a certain portion of the surface of the printing plates 7 while the black inking mechanism is inking that same portion. 110 Springs 18 are secured to the frame or pot portions of the inking mechanisms 14 and 16 and to the side frames 1 for the purpose of retaining the riders 12 of the said inking mechanisms 14 and 16 against the peripheries of the sectors 11. The riders 12 are 115 120

125 130

centrally grooved and the said grooves are engaged by means of the ends of lateral arms 19 secured to a vertically disposed rod 21 slidably and rotatably mounted on one side of one of the side frames 1, the said rod 21 being provided with a lateral extension 22 at the lower end thereof by means of which the arms 19 may be depressed and thereby prevent the engagement of both 10 riders 12 with any of the sectors 11. While the inking mechanisms 14 and 16 are thus withheld they may be shifted, by partially rotating the rod 21 and thus move the arms 19 so that the riders 12 on the blue inking 15 mechanism will engage the sectors in the plane heretofore engaged by the riders on the black inking mechanism and the rider on the black inking mechanism will then engage the sectors 11 that heretofore engaged 20 the rider 12 on the blue inking mechanism. By means of this arrangement that portion of the plates 7 which was receiving blue ink will receive black ink and vice versa. The printing cylinder 3 is provided with 25 a gear 23 which meshes with a similar gear 24 on the offset cylinder 26 rotatably mounted upon a sleeve 28, said sleeve 28 being in turn rotatably and slidably mounted upon a shaft 29 rotatably and slidably mounted 30 within the side frames 1.

The plates 7 on the printing cylinder 3 are in contact with a rubber blanket 31 secured to the periphery of the offset cylinder 26 in any suitable manner, preferably, by 35 means of a roller 32 rotatably mounted within an open space in the periphery of the offset cylinder 26 and provided with a plurality of projections 33 which engage apertures in the end of the rubber blanket 31. 40 This roller 32 is partially rotated so as to tighten the blanket 31 around the periphery of the offset cylinder 26, (the other end of the said blanket 31 being secured) by means of a lever 34 secured to the end of the 45 said roller 32.

The end of the lever 34 is provided with a thumb nut 36 which engages a slot 37 in a cam 38 movably secured to the end of the offset cylinder 26. The cam 38 is provided 50 with four recesses 39 in the periphery thereof, the purpose of which will hereinafter be set forth. A second outer cam 41 is rigidly secured to the sleeve 28 and is movably secured to the cam 38 by means of thumb nuts 55 42 secured to the cam 38 and which are arranged to engage arcuate concentric slots 43 in the secnd cam 41. The cam 41 is also provided with recesses 44, three in number, on the periphery thereof, one of the said recesses being larger than the others. The recesses 44 on the cam 41 are so arranged that when the larger recess on the said cam 41 coincides with the top-most recess 39 of the cam 38, as disclosed in Fig. 9 of the drawings, the two cams will present a continuous

periphery, except where the recesses 44 and 39 coincide, to a rider 46 rotatably mounted upon one of two levers 47, rigidly secured to the rod 52 having a scrub roller 48, with a periphery of a suitable absorbent material 70 thereon, rotatably mounted in the ends thereof and adapted to engage the surface of the offset cylinder 26 when the rider 46 drops into the coinciding recesses 44 and 39. The rider 46 is normally retained in engagement with the cams 38 and 41 by means of suitable springs 51 which are secured to the levers 47 and to the side frames 1, as indicated by dotted lines in Figs. 9 and 10 of the drawings. The levers 47 are rigidly secured 75 to the rod 52 upon which is also rotatably mounted a platen 53 in contact with the offset cylinder 26. The platen 53 is provided with a gear 54 which meshes with a gear 56 secured to the sleeve 28, the pitch of the said 80 gear 56 being of the same diameter as that of the offset cylinder 26 and the gear 24 secured thereto. Inasmuch as the gear 56 is secured to the sleeve 28 which is in turn detachably secured to the offset cylinder 26 by 85 means of the outer cam 41, cam 38 and the thumb nuts 42, as above described, it is obvious that when the said cylinder 26 is rotated the platen 53 will also be rotated at 90 the same peripheral speed.

The gear 54 is provided with an extension having a smaller gear 58 thereon which meshes with a larger gear 59 secured to the scrub roller 48. From this arrangement it will be observed that when the offset cylinder 26 is rotated, the rider 46 will travel on the adjoining peripheries of the cams 38 and 41 and prevent the engagement of the scrub roller 48 with the cylinder 26 until the coinciding recesses 39 and 44 are encountered 105 by the said rider 46 when the springs 51 will move the said scrub roller 48 into engagement with the periphery of the said offset cylinder 26. Inasmuch as the surface of the offset cylinder 26 and the absorbent surface of the scrub roller 48 are rotating in opposite directions at their point of contact, it is evident that the impression of the design on the surface of the offset roller at that point will be removed from the said offset cylinder 110 26 at each rotation thereof by the said scrub roller 48, which portion of the design will always be the address, and salutation, as hereinafter set forth.

Recesses 39 and 44 on the cams 38 and 41 120 will be arranged as shown in Fig. 9 of the drawings, when printing letters having an address thereon, so that the said recess formed by the coinciding recesses 39 and 44 will always lie at that point in the periphery of the offset cylinder 26 containing the address and salutation. It is therefore evident, that the rider 46 will be drawn into the coinciding recesses 39 and 44 and the scrub roller 48 will engage that portion of 125 130

the periphery of the offset cylinder 26 containing the impression of the address and remove the same therefrom, or whatever remains of the address after a sheet of paper has been passed between the platen 53 and the said offset cylinder 26.

By moving the outer cam 41 to the position indicated in Fig. 10 of the drawings, it will be seen that three of the recesses 39 of

- 10 the cam 38 will coincide with the three recesses 44 of the cam 41, so as to provide three recesses on the periphery of the cams 38 and 41 into which the rider 46 may drop and consequently allow the scrub roller 48 to engage the periphery of the offset cylinder 26 at three different points instead of one, as heretofore described. The object of this arrangement is to provide means for removing three addresses from the periphery of the 20 offset cylinder when printing envelops.

The shaft 29 has feathered thereto, and on each side of the offset cylinder 26, the eccentric 61. Connecting rods 62 are secured to the eccentric straps 64 on the eccentricities 61 25 and pivotally secured to levers 66 which are rigidly secured to a rock shaft 67 rotatably mounted between lugs integral with the side frames 1, so that each rotation of the shaft 29 will cause a complete forward and backward movement of the said levers 66. Connecting rods 68 are pivotally secured to the lower ends of the levers 66 and to the bottom of a reciprocating table 69 slidably mounted within the sub-frames 2 which support the 30 paper feeding mechanism. (See Figs. 1, 2, 3, 5 and 34 of the drawings).

Levers 71 are pivotally secured to the table 69 and carry a rod 72 upon which are pivotally mounted a plurality of inclined rubber fingers 73 which are arranged to rest on the top sheet of a pile of sheets of paper 74 within a suitable container 76 secured to the sub-frames 2. The container 76 is provided with a false bottom 77 which rests on 45 springs 78 secured within the bottom of the container 76 for the purpose of maintaining the forward edges of the paper against the under side of the overhanging lugs 79 on each forward corner of the said container 76.

As the table 69 is moved forward by the action of the levers 66 on the rock shaft 67, the rubber fingers 73 rest on the top-most sheet and move that sheet over a table 81 and toward the rubber feed rollers 82 which are 50 geared together and to a gear 83 feathered to the shaft 29, by means of the idler gear 85, said gear 83 being of the same pitch diameter as the diameter of the offset cylinder 26 and the gear 24 thereon, so that the rubber feed rollers 82 will have the same peripheral speed as that of the said offset cylinder 26. The friction of the inclined rubber fingers 73 is sufficient to loosen the top sheet from the pile and from the lugs 79 55 at the forward corners of the container 76

during a forward movement of the table 69 and the said lugs 79 will engage and prevent the second sheet from being fed forward until the top sheet has been removed. The return movement of the table 69 will drag 70 the rubber fingers 73 over the sheets of paper and will not produce sufficient friction, by reason of their slant, to move the paper during such backward movement.

The shaft 29 is slidably mounted within the side frames 1 and is provided with a double clutch member 84, one side of which engages a clutch portion 86 on the sleeve 28, (see Fig. 6 of the drawings.) As the sleeve 28 is connected, by means of the cams 38 and 41 to the offset cylinder 26 it is evident, that each rotation of the offset cylinder 26 will impart a complete backward and forward movement to the levers 66 secured to the rock shaft 67 at each rotation of the 85 said offset cylinder 26. One complete forward and backward movement of the paper feeding mechanism for each complete rotation of the offset cylinder is sufficient when printing letters and one address thereon. 90 I have provided means for changing the speed of the said levers 66 and the feed rollers 82, so that there will be three envelops and three address plates fed to the offset cylinder 26 at each rotation thereof, 95 and the speed of the feed rollers 82 will be increased to three times the peripheral speed of the offset cylinder 26 by means of the mechanism which may be described in the following manner: Adjacent to the gear 56 100 on the sleeve 28 is a smaller gear 87. This gear 87 meshes with a gear 88 of equal diameter rotatably mounted within the frame 1 of the machine and secured to a gear 89 which in turn meshes with a gear 91 having 105 a clutch portion 92 adapted to engage the clutch 84 on the shaft 29. The gear 89 is three times the diameter of the gear 91 with which it meshes, while the gears 88 and 87 are of the same diameter. By raising the 110 bifurcated retaining latch 93 on the opposite side of the frame and shifting shaft 29, so that the clutch 84 thereon will engage the clutch portion 92 of the gear 91 (as disclosed in Fig. 7 of the drawings) it will be 115 seen that the shaft 29 is then disengaged from the sleeve 28 and is engaged by the clutch 92 of the gear 91 rotating at three times the speed of the sleeve 28. The result will then be, that one revolution of the 120 offset cylinder 26 and the sleeve 28 attached thereto will produce one revolution of the gear 87 secured to the sleeve 28 and also one revolution of the gears 88 and 89, which are secured together. The said gears 88 and 125 87 being of the same diameter, the gears 88 and 89 will of course make one revolution for every revolution of the offset cylinder 26, but inasmuch as the gear 89 is three times the diameter of the gear 91, and the clutch 130

member 84 of the shaft 29 is engaged by the clutch portion 92 of the said gear 91, it is evident that one revolution of the offset cylinder 26, to which the sleeve 28 is secured by means of the cams 38 and 41, will produce three revolutions of the gear 91 and consequently of the shaft 29, and also the eccentrics 61 and gear 83 feathered thereto. The gear 83, meshes with the idler 85 which 10 in turn meshes with the gears on the shafts of the rubber feed rollers 82. The shaft 29 is retained in either one of two positions, that is, where the clutch 84 will engage the clutch portion 86 of the sleeve 28, as disclosed in Fig. 6 of the drawings, or where 15 the clutch 84 will engage the clutch 92 of the gear 91, as disclosed in Fig. 7 of the drawings, by means of the spring controlled latch 93 which is adapted to engage either 20 surface of an annular flange 94 on the shaft 29, and thus retain the said shaft 29 in either position.

From the foregoing, it is evident that one revolution of the offset cylinder 26 will produce three revolutions of the shaft 29 which, by means of the eccentrics 61, connecting rods 62 and levers 66, will produce three complete forward and backward movements of the reciprocating table 69 of the paper feed mechanism. This increase in the speed of the paper feeding mechanism is arranged to feed three envelopes, in place of one sheet of paper, to the offset cylinder 26 for the reason that three addresses can be easily arranged on the same space occupied by one address and the body of a letter. The distance between the feed rollers 82 and the point of contact of the offset cylinder 26 and the platen 53 is slightly less than the 40 width of a standard envelope and the reason that the speed of the said feed rollers 82 is increased is, that inasmuch as three envelopes are fed in place of one sheet of paper, I have found by actual demonstration, 45 that it is necessary to increase the speed of the said feed rollers 82 in order to carry the envelopes away from the feeding mechanism, hereinafter described, before the succeeding envelope is delivered to the said feed 50 rollers, in order to prevent one envelope from crowding on its predecessor.

The paper feeding mechanism is changed to an envelop feeding mechanism by folding back the arms 71 until the lugs on the sides 55 thereon engage the lugs on the reciprocating table 69, to which the said arms 71 are pivoted, as disclosed in Fig. 34 of the drawings. To the reciprocating table 69 is secured a spring plate 96, which has a laterally 60 extended offset portion 97 (see Fig. 35 of the drawings), adapted to engage the under side of a pile of envelopes 98 arranged in a container 99, detachably secured to the subframes 2, and having its bottom open, with 65 the exception of the ledges 101 around three

sides thereof. The container 99 is detachably secured to and rests upon the subframes 2. The container 99 is supported upon the said subframes 2 by means of the struts 230 secured to the container 99, said struts 230 70 and the container 99 being of such weight that the movement of the envelop feeding plate 96 will not dislodge the said container 99. The container 99 may be easily lifted out of place when its use in connection with the machine is not desired. On the side of the container 99, nearest the feed rollers 82 there is no ledge 101 and the vertical portion of the container 99 is partially removed and is replaced by means of a rubber lip 102, 80 which is arranged to frictionally engage the forward edge of the second envelop and prevent the same from being fed between the feed rollers 82 when the lateral extended offset portion 97 of the plate 96 engages the 85 lowermost envelop and feeds the same forward. In other words, the rubber lip 102 is provided for the purpose of preventing more than one envelop at a time from being conveyed from the container 99 to 90 the feed rollers 82. The plate 96 is detached while feeding sheets of paper, and while the plate 96 is attached, or during the process of addressing envelopes, the rubber fingers 73 are folded back upon the reciprocating 95 table 69, as shown in Fig. 34 of the drawings.

It is obvious from the above, that one sheet of paper or three envelopes will be fed between the platen 53 and the offset cylinder 100 26, according to the location of the shaft 29, at each rotation of the said offset cylinder 26. While one sheet of paper is being fed to the offset cylinder 26, at each rotation thereof, the cams 38 and 41, for the regulation of the scrub roller 48, will be arranged as in Fig. 9 of the drawings, so as to remove one address at each rotation of the said offset cylinder. When addressing three envelopes at each rotation of the offset cylinder, the cams 38 and 41 will be arranged, as disclosed in Fig. 10 of the drawings. When addressing envelopes the contact of the printing cylinder 3 with the offset cylinder 26 is prevented by turning the worm 110 screws 25 which engage worm threads on the peripheries of the eccentric disks 6 in which the shaft 4 of the said printing cylinder 3 is rotatably mounted. This will prevent contact between the cylinders 26 and 3 but will 115 not disengage the gears 24 and 23 on the cylinders 26 and 3, respectively, so that the offset cylinder 26 may still be driven by means of the handle 5 connected to the printing cylinder 3. The above described worm 120 25 and eccentric disks 6, may also be used for adjusting the contact or relative positions of the printing and offset cylinders 3 and 26 respectively.

One address plate is conveyed from a con- 125

tainer over suitable inking mechanisms and its design, consisting of an address and an appropriate salutation, is impressed on the offset cylinder 26 in its proper position relatively to the impression of the body of the letter thereon in the following manner: Above the approximate longitudinal center of the offset cylinder 26, is a rod 102 upon which is pivotally mounted, the carrier frame 103, which extends to the back of the machine and engages and retains in position the upper end of a container 104, the lower end of which rests in a suitable supporting frame 105 secured to transverse rods 106 secured to the side frames 1. The lower end of the container 104 is retained within the supporting frame 105 by means of a suitable spring latch 107 (see Figs. 4, 5 and 16 of the drawings). The upper portion of the container 104 is engaged by a hook 109 secured to a transverse portion 111 of the carrier frame 103. Rotatably mounted upon the rod 102 is the platen 112 having an extension with a gear 114 and a gear 116, said gear 116 meshing with the gear 56 secured to the sleeve 28 rotatably and slidably mounted upon the shaft 29. The platen 112 is arranged to receive parallel endless tapes 118, which are provided with suitable projections 119 at regular intervals thereof. These tapes also pass over suitable rollers 121 secured in the center or free end of the carrier frame 103.

The sleeve 28 and the rollers 121 are operatively connected to the internal mechanism of the carrier frame 103, so that the carrier tapes 118, pass from the carrier frame through slots 123 within the side frames 1, so that after the projections 119 of the tapes 118 have made top adjustment of the carrier frame 103, and have surveyed the address plates 124, the inking and addressing mechanism, in impression of the design on the address plates 124 onto the offset cylinder 26 in the following manner: Sliding on the rods 106, which are in turn secured to the side frames 1, is a carrier frame 125 having a movable hook 126 which is retained therein. Slidably mounted upon the stationary rack 126 is the address plate supporting platform 128, which extends into the container 104 and supports the address plates 124 therein. The platform 128 is connected by means of triple pawls 129 and 131, which are pivotally secured to the under side of the said platform 128, the center pawl 131 being arranged to engage the stationary rack 126 while the outer pawls 129 are arranged to engage the stationary rack 133. The pawl 131 is provided with a lateral pin 132, which is arranged to engage the outer sides of the outer pawls 129, so that when the pawl 131 is carried a sufficient distance, the lateral pin 132 thereof will engage the pawls 129 and remove the

same from engagement with the stationary rack 126. The container 104 is provided at one end with flanges 133, which are arranged to detachably engage a detachable end of the drawer, not shown. When the container 104, containing the address plates 124 is to be inserted into the machine the detachable end is removed therefrom and the flanges 133 are slipped under retaining lugs 134 on the supporting frame 105. The address plates 124 are prevented from falling out through the open end of the container 104 by means of the spring retaining latches 136 secured on each side of the container 104 and near the bottom thereof. The function of the stationary and sliding racks 126 and 127, respectively, and the platform 128, is to provide means operating in conjunction with the offset cylinder 26 and the rock shaft 67, that will convey one address plate 124 to the carrier tapes 118 at each rotation of the said offset cylinder 26. In order to perform the initial operation of moving, say a small number of address plates 124 into engagement with the tapes 118, the same may be accomplished before the carrier frame is lowered, by raising the movable rack 127 by means of the projection 127 at the upper end thereof, which upward movement will cause the rack 127 to engage the center pawl 131 and raise the platform 128 and the address plates 124 thereon until the flat edges 139 of the address plates 124 engage the spring latches 141 secured to and projecting into the container 104. These spring latches 141 are provided with extensions 142, which are engaged by inclined portions 143 on the carrier frame 103 when the same is lowered into position and the inclined portions 143 engage the extensions 142 and withdraw the springs 141 from the container 104 and from the path of the address plates 124 onto the platform 128. While the topmost address plate 124 is in this position, it is clear of the projections 119 on the tapes 118. An arm 146 is secured to the rock shaft 145, which is pivotally secured near stationary rack 126 and to the side frame 1. A lug 147 is secured to the rock shaft 145, which is adapted to engage the movable rack 127 and move the same upward a distance slightly greater, for the purpose of clearance, than the extent of one tooth on the rack 126 or 127, the said distance being equivalent to the thickness of one address plate 124. The arm 146 is operated so as to move the platform 128 upward at each rotation of the offset cylinder 26 or oscillation of the rock shaft 67 by means of a rod 148 secured to an arm 149 on the rock shaft 67 and having its other end secured to the arm 146. Each oscillation of the rock shaft 67 will operate the arm 146 and rod 148 and cause the arm 146 on the rock shaft 145 to 150

move and consequently elevate the lug 147 and raise the platform 128 a distance slightly greater than the thickness of one of the address plates 124. During this movement, the pawls 129 on the platform will each slip over and engage the tooth above on the stationary rack 126. The return movement of the rock shaft 67 will lower the lug 147 and allow the movable rack 127 to move downward of its own weight. The pawl 131 will slide over and engage the tooth above on the movable rack 127 as it moves downward, ready for the next operation.

15 As the movement of the arm 149, during an oscillation of the rock shaft 67, will produce too great an upward movement of the platform 128, I have provided an adjustable nut 151, which is adjustably secured to the 20 end of the rod 148 so that the end of the arm 146 will not be engaged until the forward movement of the rod 148 is nearly completed and only that portion of the forward movement of the said rod 148 is utilized which is 25 sufficient to raise the platform 128 the required distance.

The carrier frame 103 is provided with inwardly turned edges 152 upon which ride the offset edges 139 of the address plates 124. 30 At the proper moment, the rock shaft 67 operates the reciprocating table 128 and raises the topmost address plate 124 into the path of the projections 119 of the tapes 118, which projections carry the topmost plate 35 from the container 104 onto the edges 152 of the carrier frame 103 and over a moistening cylinder, which is disclosed in Figs. 1, 2, 4, 5, 21 and 22 of the drawings. This cylinder is also in rolling contact with the 40 printing plates 7 on the printing cylinder 3 and is composed of a perforated cylinder 154 having an outer absorbent covering 156 and a rubber coated spring 157 therein.

The space between each two coils of the 45 spring 157 may be regulated so as to regulate the flow of liquid from within the cylinder 154 to the absorbent covering 156, by means of a disk 158 having a threaded sleeve 159 adapted to engage the end 161 of 50 the cylinder 154. By this means, the supply of moistening fluid to the covering 156, through apertures of the cylinder 154 may be regulated. This fluid and the ink used for the address plates and printing plates on 55 the cylinder are mutually repulsive, so that the impressions or designs on the address plates 124 and the printing plates 7, being composed of ink will not accept the fluid from the moistening roller. Only that portion 60 of the surface of the printing and address plates bearing no design will accept the fluid. Consequently, after the address plate 124 and printing plates 7 are moistened by contact with the moistening roll, the impression or design portion only on the plates

will receive and accept the ink, whereas, that portion of the plates having no impression will not be inked for the reason that the said ink and moistening fluid dispensed are mutually repulsive. This method of printing 70 is well known in the art and need not be enlarged upon in the present specification, as it has no part in the invention.

The address plate 124 is carried over the edges 152 of the carrier frame 103 by the 75 projections 119 of the tapes 118 and between the absorbent material 156 on the roll 154 and a platen 163 rotatably mounted within the carrier frame 103, so as to insure contact of the address plates 124 with the said absorbent material 156. After leaving the moistening roll and platen 163, the address plate 124 is carried between a second platen 164 and segmental inking roller 166 rotatably mounted on the under side of the 85 carrier frame 103 of the address plate inking mechanism 167, as disclosed in Figs. 5, 23, 24 and 25 of the drawings. The platen 164 is driven by means of a gear 169 meshing with an idler 171, which in turn meshes 90 with the gear 114 of the platen 112. The gear 169 is secured to the shaft 172 of the platen 164, by means of a spring controlled arm 173, which has a lateral extension arranged to engage either one of the apertures 174 or 175 of the gear 169, (see Figs. 26 and 27 of the drawings). The other end of the shaft 172 is provided with a gear 177, which meshes with a gear 178 of the segmental roller 166. The extent of the inking surface 100 of the segmental roll 166 is sufficient to cover the entire address and salutation on the address plate, as indicated by the dotted rectangle 239 in Fig. 36 of the drawings. By releasing the arm 173 from the aperture 105 175 of the gear 169 and replacing the same in the aperture 174 of the said gear 169, the segmental portion of the roller 166 is advanced so that the salutation portion 241 of the design represented by lines A and B in 110 Figs. 24, 25 and 37 of the drawings, will not be inked by the segmental roller 166. This will advance the ink area of the segmental portion of the roller 166 so that the complete address but not the salutation will be inked. 115 This is further disclosed in Fig. 37 of the drawings, where the larger dotted rectangle 239, representing the area inked by the segmental roller 166, as will be observed, does not include the salutation, indicated by 120 smaller dotted rectangle 241. In this manner, it is evident that I have provided means whereby the same address plates 124 bearing a complete address and appropriate salutation may be inked and used for addressing 125 circular letters and the same address plates may be used for addressing envelopes, the salutation being omitted in the latter case.

After the plate 124 has left the platen 164, and segmental roller 166, it is conveyed be- 130

tween the platen 112 and the blanket 31 onto the offset cylinder 26, where the inked impression of the design is transferred to the said rubber blanket 31 in proper position, 5 relatively to the body of the letter which has been impressed or transferred thereon from the printing plates 7 on the printing cylinder 3.

Fig. 36 is a diagrammatic view of a sheet 10 of paper 235, the larger rectangle 236 in full lines at the top representing any suitable letter-head and the smaller one 237 below it, the date, the small rectangles 238 enclosed in the dotted rectangle 239 representing the name and address and the salutation 241, which is contained on every address plate 124, while the elongated rectangles 240 and 242 below, represent the body and signature, respectively, of the letter. 15 If the resulting impression on a sheet of paper 235 fed between the cylinder 26 and platen 53 shows that the address 238 and salutation 241 are a little too high or too low, relatively to the position of the 20 body of the letter, the offset cylinder 26, bearing the impression of the letter-head 236, body 240 and signature 242 of the letter, may be partially rotated without changing the location of the address 238 and 25 salutation 241 thereon by releasing thumb nuts 42 (see Figs. 9 and 10 of the drawings), which secure the cams 38 and 41 to the offset cylinder 26, (the said cams 38 and 41 being secured to the sleeve 28, which 30 is operatively connected through the gears 56, 116 and 114 to the address plate feeding mechanism), so that said address plate feeding mechanism will remain stationary while the offset cylinder 26, containing an impression 35 of the letterhead 236, body and signature 242 of the letter 235, may be partially rotated and thus adjust the relative position of the body 240 of the letter to the address 238 and salutation 241 therefor. The printing cylinder 3, being connected to the offset cylinder 26 by means of the gears 23 and 24, it is evident that the printing plates 7 40 on the printing cylinder 3 will be advanced or retarded accordingly. As the mechanism continues to rotate the address plate 124 45 after transferring its design to the offset cylinder 26, will be delivered by the projections 119 of the tapes 118 onto the runways 181 on the stationary plates 182, (see Fig. 30 of the drawings) from where the 50 said address plate 124 is moved onto an elevator 183 and inserted into a container 104, located on the front of the machine. Secured to the rock shaft 67 is a double lever 186, having a connecting rod 187 to a bell-crank lever 188 pivotally mounted upon the 55 side of the plate 182. The lower end of the bell-crank lever 188 has pivotally secured thereto a link 189 projecting through slots 192 in the plates 182 and having inwardly

turned and inclined ends 191. The inclined ends 191 are slotted so as to straddle runways 181, so that a forward movement of the rock shaft 67 will cause the inclined end 191 of the link 189 to slide over and drop 70 behind the address plate 124. The return movement of the rock shaft 67 will cause the inclined ends 191 of the link 189 to engage the rear edge of the address plate 124 and carry the same over the runways 181 and 75 onto the elevator 183, said elevator 183 being slidably mounted in the slots in the lower portion of the plates 182. The arm 186 is provided with a projection 193, which engages the short end 194 of a lever 196, 80 which, by means of the links 197, is connected to the extensions 198 of the elevator 183. As the rock shaft 67 moves during the first portion of its motion, the projections 193 engage the short arms 194 of the levers 85 196 and elevates the elevator 183 and the plate 124 thereon above the inwardly extending projections of the spring latches 136 of the container 104 (see Figs. 19, and 30 of the drawings). The same movement 90 of the rock shaft 67, by means of the connecting rods 187 and bell cranks 188, will move the links 189 and the inclined ends 191 backward over the next address plate 124, which at that time has been delivered 95 from between the platen 112 and the offset printing cylinder 26. The first portion of the return movement of the rock shaft 67, lowers the elevator 183 and the remainder of the movement, by means of the bell 100 cranks 188 and links 189, pulls a plate 124 onto the elevator 183. As each plate 124 is moved upward by the elevator 183, the plates 124 above, resting on the latches 136, are elevated until the offset ends 139 of the 105 lower address plate 124 pass the inwardly projecting portions of the spring latches 136.

It is obvious from the above, that the address plates 124 will be received from the platen 112 and offset cylinder 26 and inserted into a second container 104 in the 110 same order in which they were arranged in the container from which they were removed by the projections 119 of the tapes 118.

The operation is as follows: The printing plate 7 is first placed in a typewriter and the letter which it is desired to reproduce is typed directly onto the plate 7. The letter on the plate 7 is signed in the same 120 manner as a sheet of paper would be signed. A separate printing plate 10 may be used, having a suitable letter-head, date line, etc., thereon, which is also secured to the printing cylinder 3 and is inked and moistened 125 in the same manner as the plate 7. The container 104 is inserted into supporting frame 105 by elevating the free end of the carrier frame 103 to the position indicated by dotted lines in either Fig. 1 or Fig. 5 of 130

the drawings. By means of the projection 137 on the movable rack 127, the platform 128 is elevated from its lowest position, which is on a level with the floor of the 5 supporting frame 105, until the said table or platform 128 engages the lowermost plate 124, resting on the spring latches 136 of the container 104. If the drawer is not filled with plates, the top plate 124 is ad- 10 justed to its proper position to be fed into the path of the projections 119 on the tapes 118 by further moving the rack 127 by means of the projection 137 thereon, until the offset ends 139 of the topmost address 15 plate 124 engage the inwardly projecting portions of the spring latches 141 at the top of the container 104. By releasing the movable rack 127, it will fall of its own weight until the lower portion of the projection 137 rests on the lug 147, as disclosed in Fig. 16 of the drawings. By lowering the carrier frame 103 into position, the inclined portions 143 thereon engages the extensions 142 of the spring latches 141 and 20 withdraws the same from above the offset ends 139 of the top address plate 121. The carrier frame 103 is locked in this position by means of levers 201, pivotally mounted on the shaft 202 of the rollers 121, the said 25 levers 201 being provided with slotted hooks or extensions 203 (shown in dotted lines in Fig. 16 of the drawings) which engage suitable pins secured to the arcuate extensions 204. In this manner, the hook 203 engages 30 the top of the container 104, while offset depending portions 220 of the carrier frame 103 engage the sides of the container 104, near the top thereof, (see Fig. 20 of the drawings.) In this manner the container 104 is 35 held in perfect alignment with the carrier tapes 118. By rotating the machine by means of the handle 5 on the shaft 4 of the printing cylinder 3, the plates 7 first encounter the moistening surface 156 of the 40 moistening roller 154 and the impressions of the design on the plates 7 are inked by inking mechanisms 14 and 16 and the impressions thereon imparted to the rubber blanket 31 on the offset cylinder 26, the said 45 offset cylinder 26 being rotated with the printing cylinder 3 by means of the gears 23 and 24 secured to the said printing cylinder 3 and the said offset cylinder 26, respectively. As the offset cylinder 26 is rotated, 50 it also rotates the sleeve 28 and shaft 29 secured thereto, which in turn, through the gears 56 and 116, rotates the tapes 118. The rotation of the shaft 29, by means of the eccentrics 61, and connecting rods 62, op- 55 erates the levers 66 and the rock shaft 67. The rock shaft 67 operates the rod 148 and the movable rack 127 in time to feed an address plate 124 to the carrier tapes 118. The said address plate 124 being passed over the 60 moistening and inking mechanisms, there- 65 for, in time to be delivered onto the offset cylinder 26 and to transfer to the said offset cylinder 26, its design, consisting of an address and an appropriate salutation in proper relative position on the said offset cylinder 26 to the impression of the body and signature of a letter transferred to the said offset cylinder 26 by the said printing plates 7 on the printing cylinder 3. The movement of the rock shaft 67, occasioned 70 by the rotation of the offset cylinder 26 will actuate the reciprocating table 69 and cause the fingers 73 secured thereto to deliver a sheet of paper between the feed rollers 82 and onto the table 210 and between the offset cylinder 26 and the platen 53. The paper is deflected downward after leaving the platen 53 and offset cylinder 26 by a deflector plate 212, which will prevent the printed sheet from coming in contact with the scrub roller 48. Inasmuch as the coinciding recesses 39 and 44 on the cams 38 and 41 (see Fig. 9 of the drawings) are at that point of the periphery of the offset cylinder 26 containing the address and salutation, such impressions of the said address and salutation as remains on the offset cylinder 26, after the paper has been impressed thereon, will be removed by the scrub roller 48 which is permitted to engage the said offset cylinder 26 at that point by the entrance of the rider 46 into the said coinciding recesses 39 and 44. Each rotation of the printing cylinder 3 causes a fresh supply of ink to be added, corresponding to the impression of the letter-head, body and signature of the letter, to the offset cylinder 26 and also operates the rock shaft 67 and feeds a new address plate 124 to the carrier 80 frame 103 and also causes an impression of the design on the said address plate to be transferred to the said offset cylinder 26. Also, each rotation of the said offset cylinder 26 operates the rock shaft 67 which in turn operates the paper feeding mechanism 100 and the mechanism which delivers the used address plates 124 into the second container 104 secured to the front of the machine. 105

In printing envelopes, the shaft 29 is shifted to the position disclosed in Fig. 7 of the drawings, which will connect the shaft 29, by means of its clutch member 84 with the clutch portion 92 of the gear 91, which is traveling at three times the number of revolutions as the offset cylinder 26. Consequently, the shaft 29, and gear 83 feathered thereto, will rotate three times as fast as the said offset cylinder 26. This shifting of the shaft will not cause the carrier tapes 118 to move faster for the reason 115 that the said tapes are driven from the gear 56 secured to the sleeve 28 which always rotates at the same speed as that of the offset cylinder 26, otherwise, the peripheral speed of the said cylinder 26 and the platen 112 120

125

130

would not be the same and the address plates 124 would be rubbed over the surface of the cylinder 26 instead of being held in a rolling contact therewith. In transferring an impression of the design from three address plates 124, to the offset cylinder 26 at each rotation thereof, it is not necessary to increase the speed of the carrier tapes 118 as the number of projections 119 on the tapes 118 is such that the distance between any two projections 119 is equivalent to one-third of the circumference of the said offset cylinder. When printing letters, where only one address is required, for each rotation of the offset cylinder 26, the rock shaft 67 makes one oscillation to every revolution of the offset cylinder 26, and causes one address plate 124 to be fed to every third projection 119 of the tapes 118, consequently, only one plate is provided for every revolution of the offset cylinder 26. It is evident that the peripheral speed of the platen 112 to the offset cylinder 26 must be the same, consequently, instead of feeding the address plates 124 at a greater rate of speed, I feed a greater number of address plates 124 to the carrier tapes 118 for each revolution of the offset cylinder 26. In other words, when printing letters, one oscillation of the rock shaft 67 is made and one address plate is supplied for each rotation of the cylinder 26. When feeding envelope the oscillations of the rock shaft 67 are speeded up to three oscillations for one rotation of the offset cylinder 26. Consequently, three address plates 124 are fed to the offset cylinder 26 at each rotation thereof.

Having thus described my invention what I claim as new and desire to secure by Letters Patent is—

1. An offset printing press comprising an offset cylinder; a printing cylinder adapted to transfer a design onto the offset cylinder at each rotation thereof; and means for transferring a different addition to the design onto the offset cylinder at each rotation thereof.

2. An offset printing press comprising an offset cylinder, a printing cylinder adapted to transfer a design onto the offset cylinder at each rotation thereof; means for transferring a different addition to the design onto the offset cylinder at each rotation thereof; and means for removing the addition only to the design from the said offset cylinder at each rotation thereof.

3. An offset printing press comprising an offset cylinder; a printing cylinder adapted to transfer an impression of a letter on the offset cylinder at each rotation thereof; and means adapted to transfer an impression of a different address and an appropriate salutation on the offset cylinder at each rotation thereof.

4. An offset printing press comprising an offset cylinder; a printing cylinder adapted to transfer an impression of a letter on the offset cylinder at each rotation thereof; means for transferring an impression of a different address and an appropriate salutation on the offset cylinder at each rotation thereof; and means for removing the impression of the address and salutation only from the offset cylinder at each rotation thereof.

5. An offset printing press comprising an offset cylinder; and means adapted to transfer an impression of a plurality of different designs onto the offset cylinder at each rotation thereof.

6. An offset printing press comprising an offset cylinder; means adapted to transfer impressions of a plurality of different designs onto the offset cylinder at each rotation thereof; and means adapted to remove the plurality of impressions from the offset cylinder at each rotation thereof.

7. An offset printing press comprising an offset cylinder; a printing cylinder adapted to transfer an impression of a letter onto the offset cylinder at each rotation thereof; a plurality of plates each having a different address and an appropriate salutation thereon; means for disengaging the printing cylinder from contact with the offset cylinder; and means for transferring an impression of the address portion only from an address plate onto the offset cylinder at each rotation thereof.

8. An offset printing press comprising an offset cylinder; a printing cylinder adapted to transfer an impression of a letter onto the offset cylinder at each rotation thereof; a plurality of plates each having a different address and an appropriate salutation thereon; means for disengaging the printing cylinder from contact with the offset cylinder; means for transferring an impression of the address portion only from an address plate onto the offset cylinder at each rotation thereof; and means for removing the impression of the address from the offset cylinder at each rotation thereof.

9. An offset printing press comprising an offset cylinder; a printing cylinder adapted to transfer an impression of a letter onto the offset cylinder at each rotation thereof; a plurality of plates each having a different address and an appropriate salutation thereon; means adapted to prevent a transfer of the impression from the printing cylinder to the offset cylinder; and means for transferring an impression of the address portion only of several address plates onto the offset cylinder at each rotation thereof.

10. An offset printing press comprising an offset cylinder; a printing cylinder adapted to transfer an impression of a letter onto

- the offset cylinder at each rotation thereof; a plurality of plates each having a different address and an appropriate salutation thereon; means adapted to prevent a transfer of 5 the impression from the printing cylinder to the offset cylinder; means for transferring an impression of the address portion only of still several address plates onto the offset cylinder at each rotation thereof; and means 10 for removing the impressions of the addresses from the offset cylinder at each rotation thereof.
11. An offset printing press comprising an offset cylinder; a printing cylinder adapted 15 to transfer an impression of a letter onto the offset cylinder at each rotation thereof; a plurality of plates each having a different address and an appropriate salutation thereon; and means for transferring an impression 20 from a different address plate onto the offset cylinder at each rotation thereof.
12. An offset printing press comprising an offset cylinder; a printing cylinder adapted to transfer an impression of a letter 25 onto the offset cylinder at each rotation thereof; a plurality of plates each having a different address and an appropriate salutation thereon; means for transferring an impression from a different address plate 30 onto the offset cylinder at each rotation thereof; and means for removing the impression transferred to the offset cylinder from an address plate at each rotation of the said offset cylinder.
13. An offset printing press comprising an offset cylinder; a printing cylinder adapted to transfer an impression of a letter onto the offset cylinder at each rotation thereof; a plurality of plates each having a different 35 address and an appropriate salutation thereon; means for transferring an impression of the address portion only from an address plate to the offset cylinder at each rotation thereof; and means for removing the impression of the address from the offset cylinder at each rotation thereof.
14. An offset printing press comprising an offset cylinder; a printing cylinder adapted to transfer an impression of a letter onto 40 the offset cylinder at each rotation thereof; a plurality of plates each having a different address and an appropriate salutation thereon; means for transferring an impression from a different address plate onto the offset cylinder at each rotation thereof; and a scrub roller in peripheral contact with the offset cylinder and adapted to remove the impression transferred to the offset cylinder from the address plate at each rotation of the said offset cylinder.
15. An offset printing press comprising an offset cylinder; a printing cylinder adapted to transfer an impression of a letter onto 45 the offset cylinder at each rotation thereof; a plurality of plates each having a different address and an appropriate salutation thereon; means for transferring an impression from a different address plate onto the offset cylinder at each rotation thereof; and means adapted to prevent a transfer of the impression from the printing cylinder to the offset cylinder at each rotation thereof; and means for removing the impression transferred to the offset cylinder from the address plate at each rotation of the said offset cylinder.
16. An offset printing press comprising a rotating offset cylinder; a rotating printing cylinder adapted to transfer an impression of the body of a letter to the offset cylinder at each rotation of the said offset cylinder; a plurality of address plates each having a different address and an appropriate salutation thereon; means adapted to transfer an impression of the address and salutation from a different plate to the offset cylinder at each rotation thereof; means for removing the impression of the address and salutation only at each rotation of the said offset cylinder; and means adapted to rotate the contacting surfaces of the scrub roller 75 and the offset cylinder in opposite directions.
17. An offset printing press comprising a rotating offset cylinder; a rotating printing cylinder adapted to transfer an impression of the body of a letter to the offset cylinder at each rotation thereof; a plurality of address plates each having a different address and an appropriate salutation thereon; means adapted to transfer an impression of the address and salutation from a different plate to the offset cylinder at each rotation thereof; means for removing the impression of the address and salutation only at each rotation of the said offset cylinder; and means adapted to adjust the relative positions on the offset cylinder of the impressions from the address plates 80 and the printing cylinder.
18. An offset printing press comprising a rotating offset cylinder; a rotating printing cylinder adapted to transfer an impression of the body of a letter to the offset cylinder at each rotation thereof; a plurality of address plates each having a different address and an appropriate salutation thereon; means adapted to impart an impression of the address and salutation from a different plate to the offset cylinder at each rotation thereof; a scrub roller rotating in the opposite direction from that of the offset cylinder and in peripheral contact therewith and adapted to remove the impressions from the offset cylinder; and means adapted to prevent the peripheral contact of the scrub roller with the offset cylinder on that portion only of the offset cylinder containing an impression of the body of the letter.
19. An offset printing press comprising a rotatable offset cylinder; a suitable inking mechanism; a printing cylinder having plates thereon containing an impression of the body and signature of a letter and adapted to rotate the said plates in contact with the inking mechanism and the offset cylinder thereby transferring an impression of the body and signature of the letter to be printed onto the offset cylinder; a series of address plates each bearing an impression of a different address and an appropriate salutation thereon; means for inking the address plates; means adapted to impress an address plate onto the inking mechanism therefor and onto the offset cylinder at each rotation of the said offset cylinder; means adapted to adjust the relative positions of 100
- 105
- 110

- the impressions of the body of the letter and the impression of the address and salutation on the offset cylinder; and means adapted to remove the impression of the address and salutation only from the offset cylinder at each rotation thereof.
19. An offset printing press comprising a rotatable offset cylinder; a suitable inking mechanism; a printing cylinder having plates thereon containing an impression of the body and signature of a letter and adapted to rotate the said plates in contact with the inking mechanism and the offset cylinder, thereby transferring an impression of said printing plates onto the offset cylinder at each rotation thereof; a series of address plates each containing an impression of a different address and an appropriate salutation thereon; means for inking the address portion only of the impression on the address plates; means adapted to transfer the inked portion of the impression on the address plates onto the offset cylinder at each rotation thereof; and means for removing the impression of the address from the offset cylinder at each rotation thereof.
20. An offset printing press comprising a rotatable offset cylinder; a suitable inking mechanism; a printing cylinder having plates thereon containing an impression of the body and signature of a letter and adapted to rotate the said plates in contact with the inking mechanism and the offset cylinder thereby transferring an impression of the body and signature of the letter to be printed onto the offset cylinder; a series of address plates each bearing an impression of a different address and an appropriate salutation thereon; inking mechanism for impressing the address plates; means adapted to impress an address plate onto the inking mechanism therefor and onto the offset cylinder at each rotation of the said offset cylinder; means adapted to adjust the relative positions of the impressions of the body of the letter and the impression of the address and salutation on the offset cylinder; means adapted to remove the impression of the address and salutation only from the offset cylinder at each rotation thereof; and means operatively connected to the offset cylinder and adapted to feed a sheet of paper into contact with the offset cylinder at each rotation thereof.
21. An offset printing press comprising a rotatable offset cylinder; a suitable inking mechanism; a printing cylinder having plates thereon containing an impression of the body and signature of a letter and adapted to rotate the said plates in contact with the inking mechanism and the offset cylinder and to thereby transfer an impression of the said letter and signature onto the offset cylinder at each rotation thereof; a series of address plates each having an impression of a different address and an appropriate salutation thereon; inking mechanism adapted to ink the address portion only of the impression on the address plates; means adapted to impress an address plate onto the inking mechanism therefor and onto the offset cylinder at each rotation of the said offset cylinder; means adapted to adjust the relative positions of the impressions of the body of the letter and the impression of the address and salutation on the offset cylinder; means adapted to remove the impression of the address and salutation only from the offset cylinder at each rotation thereof; and means operatively connected to the offset cylinder and adapted to feed a sheet of paper into contact with the offset cylinder at each rotation thereof.
22. An offset printing press comprising a rotatable offset cylinder; a suitable inking mechanism; a printing cylinder having plates thereon containing an impression of a body and signature of a letter and adapted to rotate the said plates in contact with the inking mechanism and the offset cylinder and to thereby transfer an impression of the said letter and signature onto the offset cylinder at each rotation thereof; and means for shifting the inking mechanism for the address plates so as to ink the address portion only thereon; means adapted to impress an address plate onto the inking mechanism therefor and onto the offset cylinder at each rotation of the said cylinder; means adapted to adjust the relative positions of the impressions of the body of the letter and the address on the offset cylinder; means adapted to remove the impression of the address plate only from the offset cylinder at each rotation thereof; and means operatively connected to the offset cylinder and adapted to feed a sheet of paper into contact with the offset cylinder at each rotation thereof.
23. An offset printing press comprising a rotatable offset cylinder; a series of plates each having an impression of a different address and an appropriate salutation thereon; a carrier arranged to carry several plates into contact with the offset cylinder at each rotation of the said cylinder; inking means adapted to ink the impression of the address portion only of the address and salutation impression on each plate; means operatively connected to the offset cylinder and adapted to feed several envelopes into contact with the offset cylinder; one for each

- address plate, at each rotation of the said offset cylinder; and a scrub roller operatively connected with the offset cylinder and adapted to remove the impressions therefrom, at each rotation thereof.
24. An offset printing press comprising a rotatable offset cylinder; a series of plates each having an impression of a different address and an appropriate salutation thereon; a carrier arranged to carry several plates into contact with the offset cylinder at each rotation of the said cylinder; inking means adapted to ink the impression of the address portion only of the address and salutation impression on each plate; means operatively connected to the offset cylinder and adapted to feed several envelopes into contact with the offset cylinder, one for each address plate, at each rotation of the said offset cylinder; a scrub roller operatively connected with the offset cylinder and in contact therewith and adapted to remove the impressions therefrom at each rotation thereof; and means adapted to rotate the scrub roller in a direction opposite to that of the offset cylinder.
25. An offset printing press comprising a rotatable offset cylinder; a container; a series of address plates in the container each having an impression of a different address and an appropriate salutation thereon; a carrier adapted to carry several of said plates, one at a time, from the container to the offset cylinder at each rotation of the said cylinder; means adapted to convey one plate during each rotation of the offset cylinder from the container to the carrier; an inking mechanism secured under the carrier and intermediate of the container and the offset cylinder and adapted to ink the address portion only of the address and salutation impression on each address plate; an envelop container; means operatively connected to the offset cylinder and adapted to feed several envelopes, one for each address plate, one at a time, from the envelop container to the offset cylinder at each rotation thereof; and a scrub roller adapted to normally engage the periphery of the offset cylinder and to remove the impressions therefrom.
26. An offset printing press comprising a rotatable offset cylinder; a container; a series of address plates in the container each having an impression of a different address and an appropriate salutation thereon; a carrier adapted to carry several of said plates, one at a time, from the container to the offset cylinder at each rotation of the said cylinder; means adapted to convey one plate at a time from the container to the carrier; an inking mechanism secured to the carrier and intermediate of the container and the offset cylinder and adapted to ink the address portion only of the address and salutation impression on each address plate; an envelop container; means operatively connected to the offset cylinder and adapted to feed several envelopes, one for each address plate, one at a time, from the envelop container to the offset cylinder at each rotation of the said cylinder; and a scrub roller adapted to remove the impressions therefrom.
27. An offset printing press comprising a rotatable offset cylinder; a container; a series of address plates in the container each having an impression of a different address and an appropriate salutation thereon; a carrier adapted to convey several of said address plates from the container to the offset cylinder at each rotation of the said cylinder; means adapted to dampen the surface of the address plates with a fluid which is repulsive to ink; an inking mechanism secured to the carrier and intermediate of the container and the offset cylinder and adapted to ink the address portion only of the address and salutation on each address plate; a second plate container near the delivery end of the carrier; an envelop container; and means operatively connected to the offset cylinder and adapted to feed several envelopes, one at a time, from the envelop container to the offset cylinder and a like number of address plates, one at a time, from the first mentioned container to the carrier, and to receive the address plates from the delivery end of the said carrier, and insert the last mentioned plates into the second container, at each rotation of the said offset cylinder.
28. An offset printing press comprising a rotatable offset cylinder; a container; a series of address plates in the container each having an impression of a different address and an appropriate salutation thereon; a carrier adapted to convey several of said address plates from the container to the offset cylinder at each rotation of the said cylinder; means adapted to dampen the surface of the address plates with fluid which is repulsive to ink; an inking mechanism secured to the carrier and intermediate of the container and the offset cylinder and adapted to ink the address portion only of the address and salutation on each address plate; a second plate container near the delivery end of the carrier; an envelop container; and means operatively connected to the offset cylinder and adapted to feed several envelopes, one at a time, from the envelop container to the offset cylinder and a

like number of address plates, one at a time; from the first mentioned container to the carrier, and to receive the address plates from the delivery end of the carrier, and 5 insert the said plates into the second container, at each rotation of the said offset cylinder; and means adapted to adjust the position of the impressions of the address plates on the offset cylinder relatively to 10 the impression of the body of the letter thereon.

29. An offset printing press comprising a rotatable offset cylinder; a container; a series of address plates in the container each 15 having an impression of a different address and an appropriate salutation thereon; a carrier adapted to convey said address plates from the container to the offset cylinder; means adapted to dampen the surface 20 of the address plates with a fluid repulsive to ink; an inking mechanism secured to the carrier and intermediate of the container and the offset cylinder and adapted to ink the address portion only of the 25 address and salutation on each address plate as the said plate is conveyed by the said carrier; a second plate container near the delivery end of the carrier; an envelop container; and means operatively connected to 30 the offset cylinder and adapted to feed several envelopes, one at a time, from the envelop container to the offset cylinder at each rotation thereof and a like number 35 of address plates, one at a time, from the first mentioned container to the carrier, and to receive the address plates from the delivery end of the said carrier, and insert the last mentioned plates into the second container, at each rotation of the said offset cylinder; means adapted to adjust the 40 position of the impressions of the address plates on the offset cylinder relatively to the impression of the body of the letter thereon; and a serial roller adapted to normally en-

gage the periphery of the offset cylinder 45 and to remove the impressions therefrom.

30. An offset printing press comprising a rotatable offset cylinder; a container; a series of address plates within the container each plate having an impression of a different address and an appropriate salutation thereon; a carrier adapted to convey the plates from the container to the offset cylinder; an inking mechanism secured to the carrier and adapted to ink the address 55 portion only of the address and the salutation impression on each address plate; a damping roller adapted to dispense a fluid to each address plate that will permit only the impression to receive ink from the inking mechanism; a second plate container near the delivery end of the carrier; an envelop container; a rock shaft operatively connected to the offset cylinder; a platen in peripheral contact with the offset cylinder; 60 feed rollers geared to the offset cylinder; means secured to the rock shaft and adapted to feed several envelops, one at a time, to the feed rollers geared to the offset cylinder at each rotation thereof; means secured to the rock shaft and adapted to feed a like number of address plates, one at a time, from the first mentioned container to the carrier at each rotation of the offset cylinder; and means secured to the rock shaft 70 and adapted to receive the plates, one at a time, from the delivery end of the carrier and to insert the said plates into the second mentioned container in the same order that the said plates were received from the first 75 mentioned container.

In witness whereof I hereunto set my signature in the presence of two subscribing witnesses.
